Max R. Kling
ATTORNEY

UNITED STATES PATENT OFFICE.

HERMAN LUSCHER, OF FAR ROCKAWAY, NEW YORK.

CAN OPENER.

Application filed August 20, 1924. Serial No. 733,104.

To all whom it may concern:

Be it known that I, HERMAN LUSCHER, a citizen of Switzerland, residing at Far Rockaway, in the county of Queens and 5 State of New York, have invented certain new and useful Improvements in Can Openers, of which the following is a specification.

This invention relates to improvements in 10 can openers, and it is the principal object of the invention to provide an opener which is equipped with means for duly guiding it during the cutting operations, and which will positively cut the cover without danger 15 for the operator.

Another object of the invention is the provision of a can opener having a pivotally arranged knife, pointed at its end and provided with a hook-shaped head adapted to 20 hold and guide the knife during the cutting operation.

A further object of the invention is the provision of a can opener with an operating handle equipped with an angular, pointed 25 end adapted to enter the can cover in approximately its middle and to provide a support during the operation of the handle in its horizontal position.

It is also one of the objects of the invention to provide a can opener equipped with means for guiding the same during its cutting operation on the bead of the can, and with means for allowing an adjustment of the opener to cans of varying widths.

These and other objects of my invention and advantages thereof, will become more fully known as the description proceeds, and will then be specifically pointed out in the appended claims.

40 In the accompanying drawing:—

Figure 1 is a side elevation of a can with the opener constructed in accordance with the present invention in its operating position, part of the can wall being broken 45 away.

Figure 2 is a top plan view thereof.

Figure 3 is an enlarged detail view of the can opener proper and its co-operating parts in cutting position on a fragmentary portion 50 of the can.

Figure 4 is an enlarged detail side view of the cutting tool in its cutting position.

Figure 5 is a view similar to Figure 4 with the cutting tool about to enter the can.

55 The can opener comprises a horizontal arm 10 having one of its ends angularly

bent to form a finger 11 and then bent again parallel to arm 10 to form a member 12 with a pointed end 13 adapted to be pressed through the cover 14 of a can of ordinary 60 construction in approximately the center thereof having the customary marginal bead 15.

Intermediate its ends, the arm 10 carries 65 loosely sliding thereon, a bracket 16 having depending arms 17 and 18 constituting a bearing or support for a stub-shaft or bolt 19 on which is mounted between the arms 17 and 18, a roller 20 adapted to guide the tool along the marginal bead 15 of the can 70 during operation.

The shaft 19 carries also, adjacent to the depending arm 17, the cutting tool 21 pivotally secured thereto at its upper end having a frontal cutting edge 22, and a hook end 23. 75

A pin 24 projecting from the inner face 80 of the arm 17 limits the movement of the tool in one direction, and a handle on the free end of the arm 10 allows the proper operation of the device as follows:—

When it is desired to open a can, point 13 is pressed through the cover in its middle, and arm 10, which has been vertically held, is now turned to assume a substantially horizontal position while member 12 engages 85 the inner or under face of the cover. Then the tool 21 is pressed through the cover, near its marginal bead, by moving arm 10 anti-clockwise, so that the tool engages the pin 24. If now the tool is moved in the 90 direction of the motion of the hands of a clock, the hook 23 engages under the cover, while the cutting edge 22 will gradually cut the cover in the usual manner.

It will be clear that changes may be made 95 in the construction of the minor details of my device such as fall within the scope of the appended claims without departing from the spirit of the invention.

Having thus described my invention, what 100 I claim as new and desire to secure by Letters Patent, is:—

1. A can opener comprising an operating arm, a means for guiding and supporting said arm against the can cover, a bracket 105 slidable on said arm to allow an operation of the opener on cans of various widths, a pair of depending arms on said brackets a cutting tool pivotally held between said arms, and a pin on one of said arms for 110 limiting the swinging of said tool around its pivot in one direction.

2. A can opener comprising an operating arm, a handle at one end of said arm, an angular pointed means at the opposite end of said arm adapted to enter through the can cover and support said opener during its operation with the operating arm in horizontal position, a bracket sliding on said operating arm intermediate its ends allowing the use of the opener on cans of varying widths, a pair of depending arms on said bracket, a bolt shaft supported by said arms, a guide roller between said arms on

said shaft, a cutting tool pivotally held on said shaft between said arms, a pin on the inner face of one of said arms for limiting the movement of said tool in one direction, a hook-shaped pointed end on said tool adapted to be pressed through the cover and to guide said tool during the cutting operation underneath the cover, and a knife shaped edge on said tool. 15 20

In witness whereof I have affixed my signature.

HERMAN LUSCHIER.
